[57] CLAIM

The ornamental design for an anaesthesiologist light source or similar article, substantially as shown and described.

DESCRIPTION

FIG. 1 is a top front perspective view of the anaesthesiologist light source or similar article showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a side elevational view thereof, the clamp being shown in broken lines for illustrative purpose only.

FIG. 1

FIG. 2

FIG. 3

FIG. 4

FIG. 5

FIG. 6

FIG. 7

FIG. 8
